UNITED STATES PATENT OFFICE

SEIFERT W. ROUSSEAU, OF BALDWIN, NEW YORK

DOOR OPERATING MECHANISM

Application filed August 23, 1930. Serial No. 477,295.

This invention relates to door operating mechanism and pertains particularly to mechanism for operating a plurality of doors simultaneously as well as to latching means for holding the doors in various operated positions.

The object of the invention is to provide mechanism of the kind specified which is simple in its construction and operation; which will operate positively and easily at all times; which will provide adjustment in the amount of opening of one or more of the doors; and which embodies improved and convenient latching mechanism for holding the doors in place.

Other objects and advantages of the invention will appear hereinafter.

A preferred embodiment of the invention selected for purposes of illustration is shown in the accompanying drawings, in which:

Fig. 1 is a top plan view of the mechanism as applied to a pair of garage doors; taken on the line 1—1 of Fig. 2;

Fig. 2 is a vertical section on the line 2—2 of Fig. 1;

Fig. 3 is a transverse vertical section of a portion of the mechanism taken on the line 3—3 of Fig. 5;

Fig. 4 is a top plan view of a part of the mechanism; and

Fig. 5 is a longitudinal vertical section taken on the line 5—5 of Fig. 4.

Referring to the drawings, the apparatus comprises a guide member 10, preferably of a shallow channel form which may be secured to the tie beams 11 or ceiling of the building in any suitable manner. Mounted for reciprocation along the guide 10 is a traveller member 12 which preferably comprises a U-shaped member 13 embracing the guide member 10 and having a pair of shafts 14 extending transversely thereacross, the said shafts being preferably rigidly secured to the member 13 by nuts 15 which engage threaded ends of the shafts. Mounted for rotation on the shafts 14 are corresponding rollers 16 which track on the bottom of the channel portion of the guide 10.

The doors 17 which are to be operated receive their angular movement about their

hinges from the reciprocating member 12, rigid links 18, preferably of channel iron, forming the connection between the member 12 and the doors. The connection of the links with the doors may be secured by pivot pins 20 and with the member 12 by pivot pins 21. The mounting for the pivot pins 20 at the doors may comprise a member 22, preferably of angle iron, provided with a plurality of longitudinally spaced holes 23 permitting the pins to be set at different places. The mounting for the pivot pins 21 on the reciprocating member 12 may comprise a member 24, preferably of flat iron, secured beneath the U-shaped member 13 and provided on either side with a plurality of longitudinally spaced holes 25.

If both doors are to be opened to the same angular extent the links 18 are both connected with corresponding holes in the members 22 and 24, the holes selected determining the extent of opening, but if one of the doors is to be opened to a greater angular extent than the other, the link for that door may be shifted either along the row of holes in the member 22 attached to the door or along the row of holes in the member 24 attached to the reciprocating member 12. In order that the doors may close together it is usual to shift the point of attachment at both ends of the link. The latter condition is the one illustrated in the drawings, the door shown in the upper portion of Fig. 1 being opened wider than the lower door. This arrangement is desirable, for example, when the line of access to the building is not at right angles to the plane of the opening to the building—i. e. to the plane of the doors when closed.

Means is provided for holding the doors in either open or closed position. Referring to Fig. 5, it will be observed that a plunger guide 30 is secured in the cross-bar of the U-shaped reciprocating member 13 by nuts 31. Within this guide operates the latch plunger 32, the same being urged upward at all times by a coil spring 33. The upper end of the plunger engages holes 34 provided in the guide member 10. There may be any desired number of holes 34 in the member 10 but ordinarily there will at least be a hole in

position to receive the plunger for the open and closed positions of the reciprocating member 12. Herein there are shown two holes at each position thus furnishing adjustment in the extent of opening and closing. The plunger may be limited in its upward movement into the holes 34 in any approved manner for example, as by being formed conical on its end as shown.

10 Since the latch plunger is normally above reach, it is desirable to provide operating means therefor which is within reach. Further, since it is desirable to lock the doors, it is desirable to dispose the operating means in a more desirable location—as for example, on one of the doors—and to use it in connection with locking the doors. The means herein shown for this purpose comprises, a lever 35 mounted for pivotal movement in a slot 30 formed in a stud 36 secured to the lower part of the U-shaped member 13. The stud together with guide 30 may also be utilized for retaining the plate 24 to the member 13. The lever may be operated by a flexible member 37 connected to the bent up end of the lever and extending through the eyelet 38 at the pivot axis of the link groove of the link, and finally downward through the link near its end which is attached to the door locking device as shown in Fig. 2. This arrangement provides positive and free operation of the latch plunger in all adjusted and rotated positions of the link 18.

35 Since the lever 35 is shifted relative to the latch plunger 32 in operating it, the lever is slotted at its end which engages the latch plunger. The latch plunger is formed with an annular groove 39 cooperating with the slotted end of the lever 35. When the flexible member is pulled down it causes the distal end of the lever 35 to be pulled down, thereby releasing the latch plunger from the hole in the guide 10, thus permitting the doors to be swung as desired. When released, the plunger drops into the first large hole which is presented to it and thus holds the doors in the corresponding position until again released.

40 The front end of the flexible member 37 is attached to the locking lever 40 (Fig. 2) pivoted on a bracket 41 secured to the door. The lever is slotted at 42 and receives therein an eye or staple 43 adapted to take a lock 44 to hold the door closed.

45 It may be desirable when working in the building or for other reasons to secure the doors in partly open positions. To accomplish this, a small plunger 45 is mounted on the travelling device 12, preferably within the plunger 32, in position to engage small holes 46 formed in the track guide 10. This latch is biased upward by a coil spring 47 and when desired, is held downward by a cam lever 47 pivoted to the lower end of the plunger. The cam lever has flat surfaces to hold it in set positions. A member 48 fur-

nishes a convenient means for operating the cam lever.

It will be apparent that the mechanism may have various other embodiments within the spirit of the invention as set forth in the 70 subjoined claims.

What I claim is:

1. Door operating mechanism comprising in combination, two mating hinged doors, and means for co-ordinately opening said doors by either equal angles or by unequal angles, said means including a travelling member movable at right angles to the plane of the opening closed by said doors, two link members each attached at opposite ends to 75 said travelling member and to one of said doors, a bar member attached to each door and provided with a plurality of holes for selective pivotal attachment of said links, and a bar member attached to said travelling member and provided at each side with a plurality of holes for selective pivotal attachment of said links.

2. Door operating mechanism comprising in combination, a hinged door, an overhead guide track at right angles to the door when closed, a travelling member reciprocably mounted on said track, a bar attached to said travelling member and provided with a plurality of spaced holes for attaching a door operator, a bar attached to said door and provided with a plurality of holes for attaching the door operator, a door operator in the form of a rigid link adjustably connected to said bars on the travelling member and 100 door, and means to lock said travelling member to said track at different positions.

3. Door operating mechanism comprising in combination, two mating hinged doors, and means for co-ordinately opening said doors by either equal angles or by unequal angles, said means including a travelling member movable at right angles to the plane of the opening closed by said doors, two link members each attached at opposite ends to 105 said travelling member and to one of said doors, and means providing adjustable connection for said link with said travelling member and said doors respectively whereby the angle of opening of the doors may be 110 altered yet permit the doors to be fully closed together.

4. Door operating mechanism comprising in combination, a hinged door, a reciprocable member travelling at right angles to the door when closed, a guide along which said member travels, a latch on said member adapted to secure it in various positions along said guide, a link pivotally connected to said travelling member and to said door, means for connecting the end of said link to said travelling member so as to be adjustable along the axis of movement of the same, a flexible latch operator extending along the link and downward alongside said door to an acces- 130

sible position, and means operably connecting said flexible member to said latch, said means providing for angular movement and adjustment of said link relative to said 5 travelling member.

5. Apparatus as set forth in claim 4 in which said latch and flexible-member connecting means includes a lever connected to said latch and flexible member and a guide 10 means for said flexible member disposed at the axis of the link with the travelling member.

In testimony whereof, I have signed my name to this specification this 20th day of 15 August, 1930.

SEIFERT W. ROUSSEAU.
